CLAIM

The ornamental design for a display stand for perfume vials, and the like, as shown and described.

DESCRIPTION

FIG. 1 is a perspective view of a display stand for perfume vials and the like showing my new design;
FIG. 2 is a front elevational view thereof;
FIG. 3 is a left side elevational view thereof;
FIG. 4 is a top plan view thereof;
FIG. 5 is a rear elevational view thereof; and,
FIG. 6 is a right side elevational view thereof.
FIGS. 2-6 have been shown on an enlarged scale with respect to FIG. 1.

FIG. 1

FIG. 2

FIG. 3

FIG. 4

FIG. 5

FIG. 6
